FIG. 1

FIG. 2

FIG. 3

FIG. 1 is a side elevation of an assembled knockdown archery bow embodying my new design, the handle section being shown in full lines, while the separable bow limbs and the adjustable sight are shown in broken lines for illustrative purposes only.

FIG. 2 is a front elevation on an enlarged scale of the handle section, the butt end portions of the bow limbs being shown in broken lines in separated relation.

FIG. 3 is a side elevation seen from the right hand side of FIG. 2.

FIG. 4 is a rear elevation seen from the right hand side of FIG. 3.

FIG. 5 is a side elevation seen from the right hand side of FIG. 4.

FIG. 6 is an upper end view of the handle section seen from above the handle section as shown in FIG. 5, and

FIG. 7 is a lower end view of the handle section seen from below the handle section as shown in FIG. 5.

The dominant features of the design reside in the portions shown in full lines.

I claim:

The ornamental design for a handle section of a knockdown archery bow, substantially as shown and described.
